TRAIL JACK

Trevor O. Davidson, Milwaukee, Wis., assignor to
 Bucyrus-Erie Company, South Milwaukee, Wis.,
 a corporation of Delaware

Application December 9, 1943, Serial No. 513,564

14 Claims. (Cl. 280—33.44)

1

My invention relates to new and useful improvements in trail jacks for gun mounts.

In modern mobile warfare, it is essential that field artillery pieces be moved into and out of firing position with the maximum of speed. In such movings, the critical period, during which not a minute should be wasted, is the period during unhitching from and hitching to the hauling device.

Accordingly it is the principal object of my invention to devise a hitch which can be operated with such speed and precision as to reduce this period to the barest minimum.

In addition to my principal objects, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawing, which are hereinafter particularly described and explained.

Throughout the description the same reference number is applied to the same member or to similar members.

Figure 1 is a side elevation of my invention, with the trail of the gun on the ground.

Figure 2 is a side elevation of my invention, with the trail in position for traveling.

Figure 3 is a plan view of my invention, in the same position as Figure 2.

Figure 4 is a side elevation of my limber in traveling position without the cannon.

Referring to the first three figures, we see that 11 is a conventionalized representation of the mount of a field gun (not shown). It is shown as supported on four rubber-tired wheels 12.

To this mount 11 there is attached a trail 13, in any conventional manner so that the rear-end thereof can be raised from and lowered to the ground. This trail serves to brace the gun during firing, and to serve as a means for dragging the gun backwards during moving.

14 is the axle of a limber, shown as having two rubber-tired wheels 15, and a drawbar 16, which is attached to a wheeled tractor (not shown) or other highly mobile tractive instrumentality. Of course, it could equally well form a part of such instrumentality.

The wheels 15 are journaled on the ends of the axle 14, which axle is in turn journaled (as at 17, 17) to the drawbar 16. An offset curved cable-way 18 is built rigid with the axle 14, but might equally well be free to rotate thereon. in

2

which event the axle could be rigid with the drawbar 16, if desired. All that is important in this connection is that the cable-way be capable of rotating with respect to the drawbar 16. Other ground support could be substituted for wheels 15.

Pivoted on a substantially vertical pivot integral with cable-way 18 is a lever-arm 19. Other numbered parts of my invention will be mentioned as the description of its operation progresses.

My invention is operated as follows:

The rail 13 terminates in two brackets 20. When the trail is in the position shown in Figure 1, and it is desired to move the gun, the limber 15 is backed over the trail into the position shown in Figure 1. The brackets 20 are then pivotally secured to lever-arm 19, by means of a pin or bolt 21, passed through holes in the lever-arm and the bracket.

20 A rope 22, pivotally attached (preferably permanently) to lever-arm 19 at 23, passes around cable-way 18, and thence to the usual winch (not shown) possessed by the tractor (not shown).

As soon as the pin or bolt 21 has been set, the 25 winch is actuated to draw-in rope 22, which rotates lever-arm 19 and cable-way 18 about axle 14 as an axis, thus raising the trail to the position shown in Figure 2. It is to be noted that, when the parts are in this position, the connection 24 between lever-arm 19 and brackets 20 is

practically in toggle above axle 14. This not only causes axle 14 to support the weight of the trail by direct compression through lever-arm 19 without strain, but also enables the accomplishing of 30 the snug-take-up function (about to be described) by hand, inasmuch as there is practically no weight to be lifted in the course thereof.

Screw 24, which depends from trail 13 has at its lower end an eye, through which it is now 35 secured to lever-arm 19 by pin or bolt 25. Lever-arm 19 is then taken up snug against trail 13 by means of screwing hand-nut 26 down against sliding washer 28. Nut 26 is then locked by hand-nut 27.

45 The cannon can then be towed away.

Lowering the trail into place is accomplished in inverse order.

When the cannon has been towed to its firing 50 position and detached from the limber, screw 24 and associated parts, which loose from the trail, except when screwed up tight as already described, are lifted up out of place. Then, for the dual purpose of keeping this screw and associated parts from getting lost, and of firmly anchoring the parts of the limber together for

traveling without the cannon, the eye of screw 24 is now preferably pinned to lever-arm at 23 (the rope 22 preferably, but not necessarily, being unhitched), or may be left in its original attachment. Sliding washer 28 on screw 24 fits into notch 29 on segment 18. The (formerly) upper end of the screw rests in yoke 30, which is integral with cross-beam 31 of the limber, and the screw is clamped to this yoke by screwing hand-nuts 26 and 27 toward each other, one on each side of the yoke.

Having now described and illustrated one form of my invention, I wish it to be understood that my invention is not to be limited to the specific form or arrangement of parts herein described and shown.

I claim:

1. A trail jack, comprising an element adapted to be pivotally supported on a ground-engaging towing vehicle on a horizontal transverse pivot, a portion of said element in lowered position being adapted to register with a portion of the trail, when the latter is on the ground; means for pivotally securing these two portions together; an offset curved cable-way constrained to rotate with the element; and means for then rotating the element, to raise the trail off the ground, said means including a rope attached to the element, and passing over the cable-way, and thence to an actuating means; and characterized by the fact that the element has means for securing it to the trail when in raised position; said securing means comprising the following two parts, namely an attaching means supported by the trail, and means for thereby rotating the element into firm relation to the trail.

2. A trail jack, comprising an element adapted to be pivotally supported on a ground-engaging towing vehicle on a horizontal transverse pivot, a portion of said element in lowered position being adapted to register with a portion of the trail, when the latter is on the ground; means for pivotally securing these two portions together; an offset curved cable-way constrained to rotate with the element; and means for then rotating the element, to raise the trail off the ground, said means including a rope attached to the element, and passing over the cable-way, and thence to an actuating means; and characterized by the fact that the element has means for securing it to the trail when in raised position; said securing means comprising an attaching means depending from the trail, and means for raising the attaching means; said attaching means being a readily removable screw, having at its lower end an eye for attachment to the element, whereby when the towing vehicle is disengaged from the trail, the eye may be attached to a portion of the element and the screw clamped to a rigid portion of the towing vehicle.

3. A trail jack, comprising an element adapted to be pivotally supported on a ground-engaging towing vehicle on a horizontal transverse pivot, a portion of said element in lowered position being adapted to register with a portion of the trail, when the latter is on the ground; means for pivotally securing these two portions together; an offset curved cable-way constrained to rotate with the element; and means for then rotating the element, to raise the trail off the ground, said means including a rope attached to the element, and passing over the cable-way, and thence to an actuating means; and characterized by including a screw eye and two nuts, the eye being capable of attachment to the element and one

of the nuts being capable of bearing against the trail and being locked by the other nut, and being further characterized by the fact that the towing vehicle has a rigid yoke whereby, when the eye of the screw is attached to the element in raised position, the screw may be secured to the yoke by the two nuts.

4. A trail jack, comprising an element adapted to be pivotally supported on a ground-engaging towing vehicle on a horizontal transverse pivot, a portion of said element in lowered position being adapted to register with a portion of the trail, when the latter is on the ground; means for pivotally securing these two portions together; an offset curved cable-way constrained to rotate with the element; and means for then rotating the element, to raise the trail off the ground, said means including a rope attached to the element, and passing over the cable-way, and thence to an actuating means; and characterized by the fact that the cable-way is notched, and by the fact that the element has means for securing it to the trail when in raised position, said securing means comprising a readily removable screw-eye depending from the trail and having a washer thereon, and two nuts to raise and lock the screw; said element also having means for attachment to the eye when said element is in raised position, and the towing vehicle having a rigid yoke, whereby the washer can be inserted in the notch in the cable-way, and the screw can then be locked to the yoke thereby securing the element against rotation while the towing vehicle travels without the trail.

5. A trail jack, comprising an element adapted to be pivotally supported on a ground-engaging towing vehicle on a horizontal transverse pivot, a portion of said element in lowered position being adapted to register with a portion of the trail, when the latter is on the ground; means for pivotally securing these two portions together; an offset curved cable-way constrained to rotate with the element; and means for then rotating the element, to raise the trail off the ground, said means including a rope attached to the element, and passing over the cable-way, and thence to an actuating means; and characterized by the fact that the element has means for securing it to the trail when in raised position, said securing means comprising a screw-eye depending from the trail, and means for raising and locking the screw-eye.

6. In a trail jack, the combination of: an element adapted to be pivotally supported by a ground-engaging towing vehicle on a horizontal transverse pivot, a portion of said element in lowered position being adapted to register with a portion of the trail when the latter is on the ground; means for pivotally securing these two portions together; and means for then rotating the element, to raise the trail off the ground into carrying position; further characterized by the fact that in lowered position the means for pivotally securing the element to the trail is substantially below the pivotal axis of the element, and that in carrying position this means is substantially in toggle above said pivotal axis.

7. A trail jack, according to claim 6, further characterized by the fact that the element includes an off-set curved cable-way, and that the means for rotating the element includes a rope pivoted thereto, and passing over the cable-way, and thence to an actuating means.

8. A trail jack, according to claim 6, further characterized by the fact that the element has

means for securing it to the trail when in raised position; said securing means comprising the following two parts, namely an attaching means supported by the trail, and means for raising the attaching means.

9. A trail jack, according to claim 6, further characterized by the fact that the element has means for securing it to the trail when in raised position; said securing means comprising an attaching means depending from the trail, and means for raising the attaching means; said attaching means being a readily removable screw, having at its lower end an eye for attachment to the element, whereby when the towing vehicle is disengaged from the trail, the eye may be attached to a portion of the element and the screw clamped to a rigid portion of the towing vehicle.

10. A trail jack, according to claim 6, further characterized by including a screw eye and two nuts, the eye being capable of attachment to the element and one of the nuts being capable of bearing against the trail end being locked by the other nut, and being further characterized by the fact that the towing vehicle has a rigid yoke whereby, when the eye of the screw is attached to the element in raised position, the screw may be secured to the yoke by the two nuts.

11. A trail jack, according to claim 6, further characterized by the fact that the element includes an offset curved cable-way, and that the means for rotating the element includes a rope pivoted thereto, and passing over the cable-way, and thence to an actuating means; and by the fact that the element has means for securing it to the trail when in raised position, said securing means comprising an attaching means supported by the trail, and means for raising the attaching means.

12. A trail jack, according to claim 6, further characterized by the fact that the element includes a notched offset curved cable-way, and that the means for rotating the element includes a rope pivoted thereto, and passing over the cable-way, and thence to an actuating means; and by the fact that the element has means for securing it to the trail when in raised position, said securing means comprising a readily removable screw-eye depending from the trail and having a washer thereon, and two nuts to raise and lock the screw; said element also having means for attachment to the eye when said element is in raised position, and the towing vehicle having a rigid yoke, whereby the washer can be inserted in the notch in the cable-way, and the screw can then be locked to the yoke, thereby securing the element against rotation while the towing vehicle travels without the trail.

13. A trail jack, according to claim 6, further characterized by the fact that the element has means for securing it to the trail when in raised position, said securing means comprising a screw-eye depending from the trail, and means for raising and locking the screw-eye.

14. A trail jack, according to claim 6, further characterized by the fact that the element includes an offset curved cable-way and that the means for rotating the element includes a rope pivoted thereto, and passing over the cable-way, and thence to an actuating means; and by the fact that the element has means for securing it to the trail when in raised position, said securing means comprising a screw-eye depending from the trail, and means for raising and locking the screw-eye.

TREVOR O. DAVIDSON.
